UNITED STATES PATENT OFFICE

2,399,009

ELASTIC FLUID TURBINE

John H. Doran, Scotia, N. Y., assignor to General
Electric Company, a corporation of New York

Application July 25, 1944, Serial No. 546,558

3 Claims. (Cl. 253—76)

The present invention relates to elastic fluid turbines having a plurality of series-connected stages and means for extracting liquid therefrom formed by condensation of some of the elastic fluid in its passage through the turbine. Centrifugal action to which such liquid is subjected forces it radially outward and accordingly it has been the practice heretofore to remove liquid from radially outer regions of the fluid flow passages in the turbine.

The object of my invention is to provide an improved construction of elastic turbines whereby liquid or condensate may be effectively removed from the outer as well as the intermediate and inner portions of the flow passages. This is accomplished according to my invention by the provision of a plurality of concentrically spaced, preferably somewhat conical strips or rings attached to the inlet portion of a low pressure stage diaphragm for directing liquid impinging thereon into drain channels formed along the inlet edge portions of the diaphragm partitions. These can be made so as to interfere very little with the flow of steam.

For a better understanding of what I believe to be novel and my invention, attention is directed to the following description and the claims appended thereto in connection with the accompanying drawing.

In the accompanying drawing Fig. 1 illustrates a sectional view partly broken away of an elastic fluid turbine embodying my invention; Fig. 2 is an enlarged perspective view of a part of Fig. 1; and Fig. 3 illustrates a modification of my invention.

The elastic fluid turbine, Figs. 1 and 2, comprises an outer casing 1 with a plurality of axially spaced diaphragms 2, 3 attached thereto. A rotor 4 disposed within the casing has a shaft 5 and a plurality of bucket wheels 6 and 7 secured thereto. Each bucket wheel has a row of circumferentially spaced buckets 8 forming bucket passages between them. Each diaphragm is associated with one of the wheels and has a row of circumferentially spaced partitions 9 secured in known manner to an inner disk 10 and an outer band 11 and forming nozzle passages between them for properly directing elastic fluid to the respective wheels 6 and 7. On its passage through the turbine, elastic fluid discharged from wheel 6 which constitutes a higher pressure stage wheel is passed into the nozzle passages of the diaphragm 3 to be directed from the latter into the bucket passages of the bucket wheel 7 which latter constitutes a lower pressure stage.

The fluid discharged from the bucket wheel 8 contains a certain amount of liquid, water in the case of a steam turbine, which liquid upon impinging on the inlet edges of the succeeding partitions and buckets may cause considerable damage to the latter and also erosion of the surface thereof. Liquid discharged from the exit edges of the bucket blades has a direction of flow different from the direction of flow of the elastic fluid. The direction of flow of the liquid particles thrown from the buckets is partly radial and partly tangential and has a rather low velocity component in the direction of steam flow. The different direction of flow of liquid and elastic fluid and the different velocities thereof may cause substantial reduction of the efficiency of operation. To remove some of this liquid, particularly from the outer regions of the passages, the turbine casing 1 is provided with an annular channel 12 and a drain conduit 13 connected to the bottom portion thereof.

The arrangement so far described is well known in the art. According to my invention means are provided for extracting liquid, such as water, flowing through the radially inner and intermediate portions of the fluid flow passages. This means in the present example comprises three concentrically spaced, preferably conically shaped rings 14, 15 and 16 supported on the thickened inlet edge portions of the partitions 9 of the low pressure stage diaphragm 3. Liquid entrained in the elastic fluid discharged from the bucket wheel 6 in the direction of the arrows indicated in Fig. 2 impinges on the radially inner surfaces of the rings 14, 15, 16. In order to collect the liquid and to limit its circumferential flow along the rings 14 to 16 each ring is provided with a plurality of circumferentially spaced scuppers or troughs 17 each being fused or otherwise fastened along one edge of the ring. Liquid flowing into these troughs is passed into radial channels formed along the leading edges of the partitions. In the present example separate U-shaped channel members 18 are fused to the inlet edge portions of the partitions to form radial channels 19 therewith. Each trough 17 discharges through an opening 20 (Fig. 2) of the channel member 18 into the channel 19. The rings 14, 15, 16 and the troughs 17 are fused to the channel members 19, which latter therefore act as a support for the rings and troughs on the partitions. The disk 10 of the low pressure diaphragm 3 is provided with an annular groove or channel 21 having openings 22 establishing communication between the

annular channel 21 and the channels 19. The outer band 11 of the diaphragm 3 is provided with a similar annular channel or groove 23 with openings 24 establishing communication between the channel 23 and the outer ends of the radial channels 19. In addition the outer channel 23 has an opening 25 at the bottom from which liquid may be discharged into the bottom portion of the aforementioned channel 12 of the casing 1.

During operation, liquid impinging on the rings 14, 15, 16 is conducted into the different troughs or scuppers 17, whence the liquid flows into the radial partition channels 19. The liquid contained in the channels 19 of the upper diaphragm half flows radially inward through the openings 22 into the inner channel 21. From this inner channel 21 the liquid flows through the partition channels 19 of the lower diaphragm half into the outer channel 23 to be discharged therefrom through the drain opening 25 into the casing channel 12. Liquid collected by the scuppers of the lower diaphragm half also flows into the radial channels 19 and within these channels flows radially outward directly into the outer annular channel 23 to be discharged therefrom through the opening 25 into the casing channel 12.

The modification of Fig. 3 comprises a partition with a disk 26 and a plurality of circumferentially spaced partitions 27 secured at their inner ends to the disk 26. A channel member 28 corresponding to the channel members 18 of Fig. 2 is secured to the inlet portion of each partition 27 to form a radial channel 29 therewith. Liquid entrained in the elastic fluid is removed therefrom and conducted to the radial channels 29 by means of a circumferentially extending ring or cone 30 corresponding to the cones 14 to 16 of Fig. 1 and a plurality of scuppers or troughs 31 fused to the ring 30 and to the channel members 29. The scuppers in the present example are U-shaped in section and have a radial length increasing in the direction towards the channel members 28. Each of the latter has a slot 32 for receiving liquid from one of the scuppers. One leg of each trough is fused to the inner surface of the ring 30 while the other leg is slightly spaced therefrom to admit liquid flowing circumferentially along the ring 30 into the trough. The liquid conducted to the radial channels 29 is discharged therefrom through bores 33 in the disk into an annular channel 34 corresponding to the channel 21 of Fig. 2. Except for

the particular design of the troughs the arrangement of Fig. 3 is the same as that in Figs. 1 and 2.

What I claim as new and desire to secure by Letters Patent of the United States is:

- 5 1. Elastic fluid turbine including a plurality of stages each having a rotary bucket wheel and a stationary diaphragm with a plurality of circumferentially spaced partitions for conducting operating medium to the wheel, and means for extracting liquid entrained in the elastic fluid from a low pressure turbine stage comprising a circumferentially extending band secured to intermediate inlet edge portions of the partitions, separate troughs secured to the band adjacent the partitions and passages formed in the partitions and arranged to receive liquid directed thereto by said troughs.
- 10 2. Multi-stage elastic fluid turbine comprising a casing, a low pressure stage diaphragm supported in the casing and having a plurality of circumferentially spaced partitions, and means for extracting liquid entrained in the elastic fluid flowing through the turbine comprising a plurality of concentric rings secured to the inlet edge portions of the partitions at radially spaced locations thereon and channel means partly formed in the partitions and arranged to collect, receive and drain liquid impinging on the radially inner surface of said rings.
- 15 3. Multi-stage elastic fluid turbine comprising a casing, a plurality of diaphragms supported on the casing each having an inner disk, an outer band and a plurality of circumferentially spaced partitions secured at their ends to the disk and the band respectively, and means for extracting liquid entrained in the elastic fluid from a low pressure stage of the turbine, said means comprising a plurality of concentric radially spaced substantially conical rings secured to the inlet edge portions of the partitions of the diaphragm of said low pressure stage, a plurality of circumferentially spaced troughs each secured to a ring and to one of the partitions and means for extracting liquid collected in the troughs, said means including radial channels formed in the partitions, ports in the inlet edges of the partitions communicating between the troughs and said radial channels, annular channels formed in the disk and the band and communicating with said radial channels, and a drain conduit connected to the bottom of the casing and communicating with the annular channels.

JOHN H. DORAN.
